BASE FOR A TWO-WHEELED FLOOR SWEEPER

Gordon W. Goodrich, Grand Rapids, Mich., and David Painter, Glenview, Ill., assignors to Bissell, Inc., Grand Rapids, Mich.

Filed Apr. 19, 1972, Ser. No. 245,696

Term of patent 14 years

Int. Cl. D7—05
U.S. Cl. D7—175

FIG. 1

FIG. 2

FIG. 3

FIG. 4

FIG. 5

FIG. 1 is a perspective view of a base for a two-wheeled floor sweeper which embodies our new design;

FIG. 2 is a front elevation thereof;

FIG. 3 is an end elevation thereof, the other end being a substantial mirror image;

FIG. 4 is a top plan view thereof; and

FIG. 5 is rear elevation thereof.

We claim:

The ornamental design for a base for a two-wheeled floor sweeper, substantially as shown and described.
